ELMER RILEY AND CLARENCE F. YUNCKER, OF DODGE CITY, KANSAS.

RACK FOR HOLDING COOKY-BOXES.

1,345,244.

Specification of Letters Patent. Patented June 29, 1920.

Application filed April 25, 1919. Serial No. 292,594.

To all whom it may concern:

Be it known that we, ELMER RILEY and CLARENCE F. YUNCKER, citizens of the United States, residing at Dodge City, in the county of Ford and State of Kansas, have invented certain new and useful Improvements in Racks for Holding Cooky-Boxes, of which the following is a specification.

10 This invention relates to racks for displaying boxes or tins containing cookies and similar cakes and has for its object the provision of a strong, durable and thoroughly efficient device of this character by means of 15 which a plurality of such boxes or tins may be supported in rows or tiers to conveniently display the same and facilitate dispensing the contents thereof.

The invention further aims to provide a 20 display rack having a holder pivotally mounted for tilting movement thereon and provided with means for detachable engagement with a box or tin, means being provided for holding the lid of the box in open 25 position when the latter is tilted to permit the removal of the contents of said box.

The invention further contemplates the provision of a novel form of spring clamp 30 adapted to engage the rear wall of the box and means carried by the holder and coacting with the front of said box for preventing displacement thereof with respect to the holder.

A still further object is generally to improve this class of devices so as to increase 35 their utility, durability and efficiency.

In the accompanying drawings:

Figure 1 is a perspective view of a display rack constructed in accordance with 40 the present invention showing one of the boxes or tins tilted and the lid thereof supported in open position to permit the ready removal of the contents of the box;

Fig. 2 is a transverse sectional view of the 45 lower portion of the rack;

Fig. 3 is a detail perspective view of one of the box holders detached showing the same in position on the supporting rod;

Fig. 4 is a detail transverse sectional view 50 showing the means employed for securing the front end of the box in position on the holder;

Fig. 5 is a detail vertical sectional view 55 showing the manner of holding the lid of the box in open position;

Fig. 6 is a similar view showing the man-

ner of securing the rear end of the box in position on the holder.

Corresponding and like parts are referred to in the following description and indicated in all the views of the drawings by the same reference characters.

The improved rack comprises a supporting frame including spaced uprights or standards 5 connected by upper, lower and intermediate longitudinal bars or sills 6, 7 and 8 and corresponding end bars 9 to form upper and lower tiers for the reception of the boxes or tins to be displayed and indicated at 10. The lower and intermediate 70 end bars 9 are provided with registering openings to permit the passage of longitudinally disposed supporting rods 11 the latter having their opposite ends threaded for engagement with suitable clamping nuts 12. 75

Pivottally mounted for tilting movement on the rods 11 are suitable box holders each comprising a flat substantially rectangular plate 13 having its edges bent upwardly to form side flanges 14 adapted to bear against the side walls of the adjacent box or tin 10. Pivottally connected at 15 with the rear edge of each plate 13 is a spring pressed clamping flange 16 adapted to bear against and frictionally engage the rear wall of the 85 box, there being suitable anchoring hooks 17 secured to the inner face of the flange 16 the bills of which are pointed and adapted to pierce the rear wall of the paper box to prevent accidental displacement thereof. 90 When a tin box is used the bills of the hooks will press against the tin just above the bead or flange of the box. One or more springs 18 are preferably coiled around the pintle rod 19 of the hinges 15 with their 95 free ends bearing against the flange 16 and bottom of the plate 13 respectively, for normally and yieldably holding the retaining flange 16 in contact with the box.

The holders are particularly adapted to 100 form a support for paper cooky boxes of the construction shown in our companion application Serial No. 292,595 executed of even date herewith and as the mechanical construction of the box forms the subject matter of said companion application, a detail description thereof is deemed unnecessary, it being merely necessary to state that each box is provided with a metallic display front 20 having a laterally extended finger piece 21 110 and a transverse recess 22. Referring back to the box holders, it will be noted that the

forward edge of the plate 13 of each holder is bent upwardly and inwardly to form an overhanging flange 23 adapted to receive the finger piece or rib 21 on the lower edge of 5 the front 20 of the adjacent cooky box as best shown in Fig. 4 of the drawings. In order to lock the cooky box in position on the holder there is provided a sliding catch 23' mounted for longitudinal movement 10 within a loop or keeper 24 fastened to the bottom of the plate 13 and having its forward portion provided with an inwardly projecting hook 25 adapted to enter the recess 22 in the display front 20 of the box and 15 its rear end provided with an eye 26. One end of a coil spring 27 is secured to the eye 26 while the other end thereof is anchored in any suitable manner to the lower face of the plate 13, said spring serving to normally and yieldably hold the hook 25 within 20 the slot 22 with the pointed end of the hook impinging against or piercing the paper or other material of which the body of the box is formed.

25 The box holders are preferably supported on the rod 11 by means of suitable loops or 25 clips 28 fastened to the bottom of the plates 13 as best shown in Fig. 2 of the drawings, although if desired said plates may be rigidly secured to the rod and the latter journaled in the openings in the end bars of the rack frame. The inner faces of the lower and intermediate longitudinal bars 7 and 8 are preferably inclined or beveled at 29 to 30 form a firm bearing for the boxes when the latter are tilted and also to permit said boxes to be supported at the desired inclination to conveniently expose the contents thereof as indicated in dotted lines in Fig. 2. A plurality of said cooky boxes will be supported 35 on the rack and arranged in rows or tiers and when a number of said boxes are thus supported suitable loops or keepers 30 will be attached to the lower longitudinal edges 40 of the top and intermediate side bars for the reception of spring tongues 31 mounted on the covers 32 of the boxes. The function of the tongues 31 and keepers 30 is to hold the lids of the boxes in open position when 45 the boxes are tilted so as to permit the contents of the boxes to be readily dispensed without the necessity of manually holding the lids of said boxes in open position when removing the contents thereof. In using the 50 rack the cooky boxes are positioned on the plates 13 of the holders and pressed laterally against the retaining flanges 16 so as to permit the finger pieces or ribs 21 on the boxes to fit beneath the retaining flanges 23 with 55 the hooks 25 entering the adjacent slots 22 and in which position the spring tension of the retaining flanges 16 will cause the flanges to firmly grip the rear wall of the box and 60 prevent accidental displacement thereof. In order to expose the contents of the boxes it

is merely necessary to tilt said boxes forwardly and downwardly until they rest on the inclined faces 29 of the supporting frame. As the boxes are tilted forwardly the hooks 31 on the lids 32 will engage the adjacent loops or keepers 30 and support said lids in open position during removal of the contents of the boxes. When the desired supply of cakes has been removed from any particular box the latter will return to normal 75 or horizontal position by gravity, this being due to the fact that the supporting rod 11 is arranged at one side of the center of the rack. As the cake box is tilted rearwardly to normal position the hook 31 will be disengaged from the adjacent keeper 30 and thus allow the lid of the box to drop by gravity to closed position.

In order to remove any desired box and permit replacement thereof by a filled box 85 it is merely necessary to release the catch 25 and press the retaining flange 16 outwardly when the box may be conveniently detached from the adjacent holder.

It will, of course, be understood that the 90 racks may be made in different sizes and shapes and so constructed as to support any desired number of rows or tiers of cooky boxes without departing from the spirit of the invention. It will thus be seen that 95 there is provided a rack of simple and durable construction which may be used with equally good results for displaying cookies either in the original packages or in the usual boxes or tins generally employed for 100 this purpose.

Having thus described the invention, what is claimed as new is:

1. A display rack including a supporting frame, a rod secured to the frame, a holder 105 carried by the rod and mounted for tilting movement with respect to the frame, means at one longitudinal edge of the holder for engagement with a display box, and a spring pressed clamping device pivotally mounted 110 on the other longitudinal edge of the holder and adapted to frictionally engage the adjacent wall of the display box.

2. A display rack including a supporting frame, a rod mounted on the frame, a holder 115 carried by the rod and pivotally mounted for tilting movement with respect to the frame, said holder having spaced upstanding side flanges for engagement with a display box, a locking member slidably mounted on the base of the holder and provided with a hook for engagement with one wall of the box, and a spring pressed clamping member pivotally connected with the rear edge of the holder for engagement with 120 another wall of the box.

3. A display rack including a supporting frame, a box holder pivotally mounted for tilting movement on the frame, a spring pressed locking member slidably mounted 130

on the holder and adapted to enter a recess formed in the box supported on said holder, and a spring pressed clamping member pivotally mounted on the rear portion of 5 the holder and provided with anchoring spurs adapted to pierce the adjacent wall of the box.

4. A display rack including a supporting frame, a box holder pivotally mounted for 10 tilting movement on the frame and including a plate having its forward edge bent upwardly and inwardly to form an overhanging retaining flange, and its side walls bent upwardly to produce upstanding 15 flanges, and a spring pressed retaining flange pivotally mounted on the plate and provided with means for engagement with the adjacent wall of a box.

5. A display rack including a supporting frame, a box holder mounted for tilting movement on the frame and including a 20 plate having its front edge bent upwardly and inwardly to form an overhanging flange for engagement with the adjacent portion 25 of a box supported by the holder, the intermediate portion of the flange being cut-away, a spring catch slidably mounted on the bottom of the plate at the cut-away portion of the flange and provided with a 30 hooked terminal adapted to enter a recess in the adjacent face of the box, and a spring clamping member pivotally mounted on the rear edge of the plate and adapted to frictionally engage the rear wall of the box.

35 6. A display rack including a supporting frame, a box holder pivotally mounted for

tilting movement on the frame and including a plate having its forward edge bent to form an overhanging flange, a catch slidably mounted on the bottom of the plate and 40 provided with a terminal hook operating in a recess in the flange for engagement with an opening in the box, a spring pressed retaining flange pivotally mounted on the rear edge 45 of the plate, and anchoring hooks on said flange having pointed terminals adapted to pierce the rear wall of a box.

7. A display rack including a supporting frame having spaced uprights connected by upper and lower longitudinal side bars and 50 transverse end bars, the inner face of one of the lower side bars being beveled to form a seat, a rod extending horizontally of the frame and secured to the adjacent end bars thereof, loops secured to the lower longitudinal edge of one of the upper side bars of the frame, box holders carried by the rod and each including a plate having upstanding side flanges for engagement with a display box having a pivoted lid, means disposed at the front and rear of each box holder for engagement with the adjacent walls of a box supported thereby, and a hook carried by the lid of each box and adapted to enter the adjacent loop for holding 55 said lids in open position when the box holders are tilted on the supporting frame to expose the contents of said boxes.

In testimony whereof we affix our signatures.

ELMER RILEY. [L.S.]
CLARENCE F. YUNCKER.
